REFRIGERATOR DRIP PAN

William Benton McMillan, St. Louis, Mo., assignor
to Hussmann-Ligonier Company, St. Louis, Mo.,
a corporation of Delaware

Application February 10, 1934, Serial No. 710,630

9 Claims. (Cl. 62—103)

My invention relates to refrigerator drip pans and more particularly to such pans as used with refrigerant coils included in cooling units of the mechanical type.

5 With cooling coils it is necessary to provide a pan below the coil to collect moisture condensed on the coil when the warmer air in the refrigerator being cooled comes in contact with the cold surfaces of the coil. These drip pans, as heretofore used, were imperforate plates supported directly from the coil by any suitable metal bracket and, therefore, the drip pan due to the conductivity of the brackets was maintained at a temperature almost as low as that of the coil 10 so that air in the refrigerator coming in contact with the pan would lose more of its moisture content than was lost on the cooling coil. In refrigerators as now being manufactured the cooling coil is usually placed at the top or other 15 point above the bottom of the storage compartment so that as the air in the storage compartment is cooled by the coil it falls downwardly onto the foodstuffs and convection currents are maintained. When the imperforate drip pans, as heretofore used, were mounted on the cooling coil so as to have a conductive connection therewith, as described above, two major deficiencies 20 of structure, among others, resulted; first, since the temperature of the pan was low moisture 25 would condense thereon and then drip onto the foodstuffs and onto the walls of the storage compartment and second, the convection currents were impaired by the imperforate pan mounted directly below the coil.

30 The objects of my invention are to provide a drip pan of the kind described which is insulated from the cooling coil and to provide a pan which allows free movement of the air downwardly from the coil.

35 One embodiment of my invention is shown in the accompanying drawing wherein similar characters are used to designate similar parts: Fig. 1 is a partial cross section of a refrigerator show case including a coil and a drip pan made according to my teachings; Fig. 2 is a longitudinal section along the lines 2—2 in Fig. 1; Fig. 3 is a view along the lines 3—3 in Fig. 1; Fig. 4 is a view along the lines 4—4 in Fig. 1; and Figs. 5 and 6 show modified details of construction of 40 the pan.

45 Referring to the figures the cabinet A of the refrigerator has suspended from the top wall B thereof a cooling coil C of usual design and adapted to be intermittently supplied with a cooling agent from a compressor, not shown. The

coil C is mounted on the top wall B by means of suitable fixtures, such as brackets D and D', which are supported by bolts E and which are adapted to clamp the coil firmly in place.

50 Also, suspended from the top wall B, in this embodiment, is a drip pan generally indicated by the character F. The pan F is carried by arms G mounted on suitable studs H and comprises an upper part consisting of a pair of plates J spaced apart at their adjacent edges and a lower part K 55 provided with a plurality of elongated openings L arranged as hereinafter described. The two parts of the drip pan F are maintained in fixed relation by a plurality of blocks M, preferably, of non-conducting material. The parts of the pan 60 are preferably inclined downwardly towards the center thereof, as clearly shown in Fig. 1, so that a sump will be formed in which moisture dripping on the pan will collect. The moisture so collected drains from the refrigerator through 65 a drain pipe N leading to a suitable place of discharge. The outer side edges of the plates J, the similar edges of the lower part K and the bounding edges of the openings L, preferably, are provided with longitudinally extending up-turned 70 flanges O. Likewise, the adjacent edges of the plates J are provided with downwardly extending flanges O'.

75 The plates J are spaced apart, as described above, to provide a longitudinally extending opening therebetween through which moisture may pass and through which air may flow downwardly from the coil. The openings L in the lower part K of the pan are positioned out of 80 register with the space between the plates J so 85 the pan will collect all moisture dripping from the coil, but will allow a free downward movement of air.

90 While in the accompanying drawing the pan is 95 insulated from the coil by being mounted separately therefrom, if desirable, the pan may be mounted directly on the coil by means of suitable insulated brackets or fixtures. Due to the proximity of the plates J to the cooling coil, these plates may be cooled slightly, but the lower part K of the pan as it is insulated from the plates will be at substantially the temperature of the air in the storage compartment and little or no moisture will be condensed on the lower surfaces thereof. However, in some instances, it will not be necessary to insulate the two parts of the pan from each other and in such event a single bracket G', as shown in Fig. 5, may be used to support both 100 parts of the pan.

105 With the use of my new and improved pan, as

described and shown herein, the deficiencies of structure heretofore present will be obviated; the pan will not be cooled to any appreciable extent, all condensation from the coil will be collected 5 and a free downward movement of air from the coil will be allowed. The flanges O will prevent moisture from passing over the edges of the various parts of the pan and the flanges O' will allow the moisture to drip from the plates J into the 10 sump formed by the lower part K.

It should be understood distinctly that although I have shown only one embodiment of my invention I do not wish to be limited to this showing because the size, shape, position and 15 arrangement of the various parts may be varied within wide limits without deviating from the spirit of my invention as included in the appended claims.

What I claim as new and desire to secure by 20 Letters Patent, is:—

- 20 1. In combination with a refrigerator having a cooling coil positioned therein above the storage compartment thereof of a drip pan mounted out of thermal contact with said coil whereby said pan is not directly cooled thereby and said pan comprising a plurality of parts arranged in different planes and insulated from one another and each adapted to collect condensation from said coil.
- 25 2. In combination with a refrigerator having a cooling coil positioned therein above the storage compartment thereof of a drip pan mounted out of thermal contact with said coil whereby said pan is not directly cooled thereby and said pan comprising a plurality of parts arranged in different planes and said parts each having openings therethrough with an opening in one part being out of register with the openings in the other part whereby said pan will collect condensation.
- 30 3. In combination with a refrigerator having a cooling coil positioned therein above the storage compartment thereof of a drip pan comprising an upper part and a lower part having non-registering openings therethrough to allow free movement of air downwardly from said coil and each of said parts being adapted to collect condensation from said coil.
- 35 4. In combination with a refrigerator having a cooling coil positioned therein above the storage compartment thereof of a drip pan comprising an upper part having an elongated opening therethrough and a lower part having a plurality of

openings out of register with the opening in said upper part whereby free movement of air downwardly from said coil will be allowed.

5 5. In combination with a refrigerator having a cooling coil positioned therein above the storage compartment thereof of a drip pan mounted out of thermal contact with said coil, said pan comprising an upper part and a lower part insulated from one another, and said parts having non-registering openings therethrough to allow free movement of air downwardly from said coil.

10 6. In combination with a refrigerator having a cooling coil positioned therein above the storage compartment thereof of a drip pan separately mounted from said coil, said pan comprising an upper part and a lower part having non-registering openings therethrough to allow free movement of air downwardly from said coil and said lower part being arranged to form a sump to collect moisture from said coil.

15 7. In combination with a refrigerator having a cooling coil positioned therein above the storage compartment thereof of a drip pan separately mounted from said coil, said pan comprising an upper part having an elongated opening therethrough and a lower part having a plurality of openings out of register with the opening in said upper part whereby free movement of air downwardly from said coil will be allowed.

20 8. In combination with a refrigerator having a cooling coil positioned therein above the storage compartment thereof of a drip pan separately mounted from said coil, said pan comprising an upper part and a lower part insulated from one another and said upper part having an elongated opening therethrough and said lower part having a plurality of openings out of register with the opening in said upper part, said lower part being arranged to form a sump to collect condensation from said coil.

25 9. In combination with a refrigerator having a cooling coil positioned in the storage compartment thereof of a drip pan mounted out of thermal contact with said coil whereby said pan is not directly cooled thereby and said pan comprising a plurality of parts arranged in different planes and insulated from one another, each of said parts being adapted to collect condensation from said coil, and each of said parts having an opening therethrough to allow movement of air downwardly from said coil through said pan.
